UNITED STATES PATENT OFFICE

HAROLD F. ELLIOTT, OF PALO ALTO, CALIFORNIA, ASSIGNOR, BY DIRECT AND MESNE ASSIGNMENTS, TO VICTOR TALKING MACHINE COMPANY, OF CAMDEN, NEW JERSEY, A CORPORATION OF NEW JERSEY

RADIO PICK-UP SYSTEM

Application filed March 11, 1927. Serial No. 174,456.

This invention relates to a system for picking up radio energy, and serves as a substitute for the usual antenna or loop circuit.

In my prior application, Serial No. 50,478, 5 entitled Radio receiving system and filed August 15, 1925, I describe a receiver circuit in which a part thereof, exclusive of the radio frequency circuit, acts as one capacity area of an open absorbing circuit; and I specifically describe how the loud speaker or either of 10 the batteries can be so utilized. My present application is a continuation in part of this earlier application, and is intended to cover certain alternative embodiments some of 15 which only, are shown in the earlier application.

It is one of the objects of my invention, therefore, to make it possible to eliminate the usual antenna or loop.

It has been proposed in the past to utilize 20 all of the receiver circuits as a capacity area; but such a system is not practical in a multi-tube set for several reasons. One is that tuning of such a set would be difficult, due to the effects of body capacity; and another is that 25 it is disadvantageous not to shield the radio frequency circuits, especially when a number of radio frequency stages are used. Such shielding of course would effectively prevent 30 the absorption of any energy at all in the system. With my arrangement, such shielding can be retained, and yet a portion of the system that is not shielded can be used as a capacity area. In this way, a very selective 35 and sensitive circuit can be obtained.

My invention possesses many other advantages, and has other objects which may be made more easily apparent from a consideration of several embodiments of my invention.

For this purpose I have shown a few forms in 40 the drawings accompanying and forming part of the present specification. I shall now proceed to describe these forms in detail, which illustrate the general principles of my invention; but it is to be understood that this de-

tailed description is not to be taken in a limiting sense, since the scope of my invention is best defined by the appended claims.

Referring to the drawings:

Figure 1 is a front view of a radio set showing one form of my invention;

Fig. 2 is a wiring diagram thereof; and

Figs. 3, 4, and 5 are diagrams of other embodiments of my invention.

In Fig. 1 I show a cabinet 11 intended to 55 house a radio set; and adjacent thereto or supported thereon, an electric lamp 12 of the usual table variety, for casting a light on the set. In this form of my invention, I utilize the metal parts of the lamp as a capacity area 60 to provide an open circuit pick-up system. This is accomplished by the aid of a system of connections which is exemplified in Fig. 2.

In this figure, I show a common type of 65 radio set circuit, including one or more radio frequency amplifier stages, such as 13, each of which can have a tunable circuit 14 to which a pick-up circuit can be coupled. Then there is the usual detector stage 15, and one or more audio frequency stages 16, the 70 last one of which has, in its output circuit, a translating device, such as loud-speaker 17. All this is shown merely diagrammatically 75 since such circuits are well-known, and I do not desire to limit myself to any particular variety, although in substantially all forms, so-called "audions" 18 and 19 or their equivalents are used to provide the detecting and amplifying functions.

I shall now describe how a pick-up system 80 is formed with the lamp 12 providing a capacity area. The lamp is shown as fed through a plug 20 adapted to be inserted into the usual outlet, and twin conductors 21. The capacity between this supply circuit and the 85 metallic isolated parts of the lamp, such as the metal base, is indicated by the condensers 22. The twin conductors 21 are formed into a coil 23 which is coupled to coil 24 of the tunable circuit 14. Since both conductors are 90

used to form coil 23, the power hum is compensated therein. It is thus seen that the open pick-up circuit includes the metallic parts of lamp 12, coil 23, and the mains forming the house supply, and which is usually grounded somewhere along its length. If it is not, these mains simply serve as the counterpoise for the metallic area of the lamp 12.

If desirable, another coupling can be effected between the lamp capacity area and circuit 14. For this purpose, a conductor 25 is electrically connected to a metallic portion of the lamp support, which portion is insulated from the usual current carrying parts of the lamp 12. This conductor 25 has a coil 26 in series therewith, which is inductively coupled to circuit 14; and a ground 27 completes this supplementary pick-up system.

In Fig. 3 I disclose a scheme whereby the B battery or B battery eliminator 28 serves to provide a capacity area for an open circuit pick-up system. The amplifying and detecting system is shown diagrammatically at 29 and 30, and the loud-speaker or phones at 31. The leads 35 from battery 28 or its equivalent (three leads in this instance) connect to appropriate posts 32, 33 and 34 of the set. The triple conductor 35 is formed into an inductance coil 36 coupled to coil 37 of the tunable circuit 29. The pick-up system is thus formed by the metallic mass of element 28, coil 36, and ground 38 provided on the set.

It is also possible to use other elements for providing the capacity area. Thus in Fig. 4, I utilize the source of electrical energy 39 for the filaments, for this purpose. This can be a storage battery or its equivalent. The amplifying and detecting system is similar to that already discussed. The source 39, instead of being directly connected across the filaments 40, 41, and 42 of the various thermionic devices, includes preferably a portion of the coil 43 of the tunable circuit 44, as well as a choke coil 45 to prevent radio frequency currents from flowing directly to ground. The inclusion of a portion of coil 43 serves as a coupling between the pick-up system and the input side of the system.

The pick-up system includes element 39, a portion of coil 43 and ground 46. Element 39 serves as a capacity area.

In Fig. 5, I show still another form of my invention. The amplifying and detecting system is similar to those already described, and includes the tunable circuit 47 with its coil 48. In this instance, an A and B battery eliminator 49 is used, from which leads 50 extend to the appropriate elements of the set. This eliminator is shown as fed from mains 51 through an iron cored transformer 52, the core 53 of which is grounded at 54. In order to form the open circuit pick-up system, the leads 51 are formed into a double wound coil 55 which is coupled to

coil 48. The distributed capacity between core 53 and the primary winding 56 of transformer 52 is represented by condensers 57 and 58. The pick-up system thus includes lines 51, coil 55, capacities 57 and 58, core 53 and ground 54. Due to the twin conductor winding of coil 55, the power hum is compensated.

In all the forms of my invention herein illustrated, some element of the power supply is utilized to provide a capacity area for the pick-up system.

I claim:

1. In a radio receiving system, means for receiving electrical impulses and acting upon the received impulses to make them perceptible, said means including devices to which electrical energy must be passed, means for supplying electrical energy to said devices, said means including a plurality of leads formed into a multiple conductor transformer winding coupled to the input side of the system, and means providing a counterpoise for that part of the supplying means which connects to the leads to form an absorbing circuit.

2. In a radio receiving system, means for receiving electrical impulses and acting upon the received impulses to make them perceptible, said means including one or more electronic emission devices, means for supplying electrical energy to said devices, said means including a pair of leads wound to form a twin conductor transformer winding coupled to the receiving means, and means providing a counterpoise for that part of the supplying means that connects to the leads to form an absorbing circuit.

3. In a radio receiving system, means for receiving electrical impulses and acting upon the received impulses to make them perceptible, said means including one or more electronic emission devices, said devices requiring electrical energy for their operation, a device for modifying electrical energy to a form suitable for supplying said required electrical energy and connected to said electronic emission devices, a transformer transmitting energy to said modifying device, and a pair of conductors connected to the primary of the transformer and forming a transformer coil coupled to the receiving means, said conductor being arranged to be connected to a source of energy, whereby at least some of the connections to said source serve as a capacity area for an open circuit pick-up system that is coupled to the receiving means.

4. The combination as set forth in claim 3, the transformer having a core which is grounded, to form a counterpoise for the capacity area.

5. The combination as set forth in claim 3, in which the coupling of the leads to the receiving means is effected by a coupling coil

formed by winding the doubled leads into a helix.

6. The combination as set forth in claim 3, in which the coupling of the leads to the receiving means is effected inductively by a coupling coil formed by winding the doubled leads into a helix, and the transformer has a core which is grounded, to form a counterpoise for the capacity area.

10 In testimony whereof I have hereunto set my hand.

HAROLD F. ELLIOTT.
